PNEUMATIC CLUTCH FOR STARTERS

Filed Dec. 9, 1929

UNITED STATES PATENT OFFICE

ANDRÉ MORTON, OF PARIS, FRANCE

PNEUMATIC CLUTCH FOR STARTERS

Application filed December 9, 1929, Serial No. 412,887, and in France July 16, 1929.

My invention relates to improved pneumatically controlled connecting means, chiefly adapted for pneumatic starters of any type for instance of the type disclosed in my co-pending application No. 347,977 filed on March 18, 1929.

Starters for internal combustion engines are generally provided with so-called "Bendix" devices comprising a pinion moving 10 longitudinally on the starter shaft and engaging when the starter is operative a toothed wheel driving the crankshaft of the internal combustion engine. But these devices are rough and in the case of electric starters, it 15 has been attempted to replace them by electromagnetic devices such as an electromagnet energized when current passes through the starter for making the pinion slide over the shaft.

20 The object of my invention is to replace Bendix devices in pneumatic starters. To accomplish this I use a pinion slidably secured to the shaft of the starter so as to rotate integrally therewith. The starter shaft is hollow and inside it may move a piston rigidly secured to the pinion and urged by a spring into a position for which the pinion is disengaged from the gearwork of the motor to be driven. When starting, the compressed air 25 or gas driving the starter passes into the shaft and drives the piston whereby the pinion is brought into engagement with the motor gearwork.

30 On appended drawing I have shown such an arrangement applied to the starter described in my above mentioned application. But obviously this connecting gear may be used with any type of starter and not exclusively with the one mentioned hereinabove.

35 The starter rotor 9 is secured to the hollow shaft 31 by a key 31a and carries in its cylindrical bores pistons 13 and 14 the ends of which are provided with rollers 15 and 16 bearing against the guiding slopes 8 on the stator; the inlet port 5 and outlet port 55 are provided in the distributor plate 43 on the opposite side of the stator. The rotor shaft 31 is carried by a ball bearing 32, an ordinary bearing 33 and if required an outer bearing 34. Inside this shaft is slidably disposed

piston 35 secured through a pin 36 passing through elongated apertures of the shaft to a sleeve 38. This sleeve 38 carries the pinion 21 which is to engage and to disengage the toothed wheel 39 on the engine to be started. 55 The sleeve 38 is slidably mounted on the hollow shaft 31 and is driven thereby through the agency of a longitudinal key 38a.

A spring 41 is secured on one hand to the piston 35 and on the other to the key 42 60 passing through the blind end of the hollow shaft 31. It urges the piston 35 towards the right so as to release the pinion 21 from engagement with the wheel 39.

In the distributor plate 43 is provided a 65 duct 5 which brings the compressed fluid e. g. compressed air to the rotor for driving same. A channel 44 allows this air to pass into the chamber 45 and from there through the port 46 inside the hollow shaft 31

70 The air tightness of the chamber 45 is ensured by the cup shaped leather packings 47 and 48, the latter being secured between the washers 49 and 50 by means of nuts 51 so as to be integral with the hollow shaft 31. 75

The operation of this improved connection is as follows: As soon as compressed air enters the duct 5, it causes the rotor and therewith its shaft to rotate and simultaneously enters through 44, 45 and 46 inside said shaft, 80 urging leftwards the piston 35 against the antagonistic spring 41. This causes the pinion 21 to engage the toothed wheel 39. As soon as compressed air ceases flowing into the starter, the piston 35 returns towards the 85 right under the action of its spring and the starter is thus disconnected from the engine to be started.

90 The rotor is caused to bear against the distributor plate by reason of the difference between the diameter given to the pistons and that given to the apertures provided at the inner end of the rotor cylinders and also of the pressure exerted on the leather packing 48 and transmitted thereby to the rotor shaft. 95 This latter arrangement is of use with the starter shown but may be unnecessary in starters of a different type in which case the fluid tightness of the chamber 45 may be ensured by any other suitable means. 100

What I claim is:

1. In a compressed air motor for starting internal combustion engines comprising a stator, a hollow rotary shaft, a rotor keyed thereto and a distributor plate on the stator, the combination of a gear wheel on the engine to be started, a pinion slidably mounted on the hollow shaft and adapted to engage said gear wheel, a piston slidably mounted 10 inside the hollow shaft and moving integrally with said pinion, yielding means urging the piston in one direction and means for feeding compressed air to the hollow shaft for making the piston move in the opposite direction.
2. In a compressed air motor for starting internal combustion engines comprising a stator, a hollow rotary shaft, a rotor keyed thereto and a distributor plate provided with 20 inlet and outlet ports and with an axial chamber around the rotary shaft, the combination of a gearwheel on the engine to be started, a pinion slidably mounted on the hollow shaft and adapted to engage said gearwheel, a piston slidably mounted inside the hollow shaft and moving integrally therewith, yielding means urging the piston in one direction, means connecting the inlet port with the axial chamber and means connecting the said axial 25 chamber with the inside of the hollow shaft at the end of the latter towards which the piston is urged by the yielding means.
3. A compressed air motor for starting internal combustion engines comprising a cylindrical stator, a distributor plate provided 30 with admission and exhaust ports closing one end thereof, a second plate closing the other end thereof, a cylindrical cam raised on the inner side thereof, a hollow shaft, a rotor borne thereby adapted to rotate inside the stator and provided with a plurality of cylindrical bores, pistons adapted to slide in the rotor 35 bores, rollers disposed between the outer end of the pistons and the cam, a gearwheel on the engine to be started, a pinion slidably mounted on the hollow shaft and adapted to engage said gearwheel, a piston slidably mounted inside the hollow shaft, means connecting rigidly the pinion with lastmentioned piston and passing through the slot in the hollow shaft, a spring urging last- 40 mentioned piston inwards into a position for which the pinion disengages the toothed wheel, a duct connecting the compressed air admission port with the axial chamber in the distributor plate and means connecting the axial chamber with the inside of the hollow shaft at the end of the latter towards which the piston is urged by the yielding means.
4. A compressed air motor for starting internal combustion engines comprising a cylindrical stator, a distributor plate provided 45 with admission and exhaust ports closing one end thereof, a second plate closing the other end thereof, a cylindrical cam raised on the inner side thereof, a hollow shaft provided with a small longitudinal slot, a rotor borne thereby adapted to rotate inside the 50

stator and provided with a plurality of cylindrical bores, pistons adapted to slide in the rotor bores, rollers disposed between the outer end of the pistons and the cam, a gearwheel on the engine to be started, a pinion slidably mounted on the hollow shaft and adapted to engage said gearwheel, a piston slidably mounted inside the hollow shaft, means connecting rigidly the pinion with last mentioned piston and passing through the slot in the hollow shaft, a spring urging last- 55 mentioned piston inwards into a position for which the pinion disengages the toothed wheel and means whereby compressed air is diverted from the admission ports and enters the hollow shaft at the end towards which the piston is urged by the yielding means.

5. A compressed air motor for starting internal combustion engines comprising a cylindrical stator, a distributor plate provided with admission and exhaust ports and with an axial chamber closing one end thereof, a second plate closing the other end thereof, a cylindrical cam raised on the inner side thereof, a hollow shaft passing through the axial chamber in the distributor plate provided with a small longitudinal slot, a rotor borne thereby adapted to rotate inside the stator and provided with a plurality of cylindrical bores, pistons adapted to slide in the rotor bores, rollers disposed between the outer end of the pistons and the cam, a gearwheel on the engine to be started, a pinion slidably mounted on the hollow shaft and adapted to engage said gearwheel, a piston slidably mounted inside the hollow shaft, means connecting rigidly the pinion with last- 60 mentioned piston and passing through the slot in the hollow shaft, a spring urging last- 65 mentioned piston inwards into a position for which the pinion disengages the toothed wheel, a duct connecting the compressed air admission port with the axial chamber in the distributor plate and means connecting the axial chamber with the inside of the hollow shaft at the end of the latter towards which the piston is urged by the yielding means.

6. In a compressed air starter as claimed in claim 5 the provision of two cup shaped packings closing the axial chamber in the distributor plate, the packing nearer the engine to be started bearing against the plate wall, and the other being secured to the hollow shaft.

In testimony I have affixed my signature.

ANDRÉ MORTON.
